RATION OF DELAWARE.

VALVE MECHANISM.

1,149,365.

Specification of Letters Patent.

Patented Aug. 10, 1915.

Application filed July 27, 1914. Serial No. 853,501.

To all whom it may concern:

Be it known that I, HIRAM A. HATFIELD, a citizen of the United States, and a resident of Nogales, in the county of Santa Cruz 5 and State of Arizona, have made certain new and useful Improvements in Valve Mechanisms, of which the following is a specification.

My invention relates to improvements in 10 valve mechanisms to be used on railroad cars, and it consists in the combinations, constructions, and arrangements herein described and claimed.

An object of my invention is to provide a 15 device which is to be used in connection with an automatic triple valve for setting the brakes by increasing the train pipe pressure above normal.

A further object of my invention is to provide 20 a device of the type described which will act perfectly, regardless of the weight or tonnage of a car or the different train line pressures.

Other objects and advantages will appear 25 in the following specification and the novel features of the device will be particularly pointed out in the appended claims.

My invention is illustrated in the accompanying drawings forming part of this application in which—

Figure 1 is a central vertical section 30 through the device, Fig. 2 is a reduced section along the line 2—2 of Fig. 1, and Fig. 3 is a diagrammatic view showing the application of the improved valve mechanism to a train controlling means.

In the following specification I will describe completely the novel valve mechanism and the operation thereof and only so much 40 of the ordinary mechanism which co-operates therewith as will be sufficient for a clear understanding of the use and operation of my invention.

In carrying out my invention I provide a 45 valve casing 1 of suitable shape. In the present instance I have shown this as a cylinder having a top 2 which may be secured to the body portion in any suitable manner, and which is provided with a pipe 2^x leading to an auxiliary reservoir (not shown). Within the interior of the valve casing is a valve member 4. This consists 50 of a weight which is provided at its upper end with a closure 4^y arranged to cover a

port 5. Packing rings 6 are provided for 55 the weighted valve. A lower closure member 4^x is designed to control a port 7. A bypass 8 is arranged in the wall of the casing 1 for a purpose hereinafter explained. In the body portion 1 below the chamber in 60 which the valve 4 operates is a cylindrical bore 9 in which is disposed a cylindrical valve piston 10. This piston, as will be seen from Fig. 1, is not provided with packing rings, but is designed to work loosely in the 65 bore 9 under the action of the air, as will be explained hereinafter. A screw plug 11 is provided for closing the end of the bore. The valve 10 has a projecting portion 10^x for limiting the movement of the valve toward 70 the plug. At 12 is shown an exhaust port. A passage 13 communicates with the interior portion 9 of the bore at both ends of the cylindrical piston valve 10 and with pipe 14. The pipe 14 in turn communicates with a 75 triple valve mechanism shown in Fig. 3.

The lower end of the valve casing 1 is provided with a threaded portion 15 arranged to receive the union 15^x which secures the end of the pipe 16 to the valve 80 casing and in communication with the passage 17.

From the foregoing description of the various parts of the device the operation thereof may be readily understood. 85

In Fig. 3 I have shown the pipe 16 as being connected directly to the drain plug of the automatic triple valve. When an overcharge of air pressure is supplied to the main train line at the engine to set the brake, 90 air passes from the main train line through pipe 16, thence through the passage 17 and port 7 where it unseats the weighted valve 4. This allows the air to pass the lower valve member 4^x and thence by means of 95 the passage 18 into the bore 9, thus forcing the piston valve 10 in the direction shown by the arrow in Fig. 1. This uncovers the passage 13 and covers the exhaust port 12. The air now flows through the passage 13 100 and through the pipe 14 and is delivered through this pipe to the exhaust of the triple valve and on to the brake cylinder, thereby setting or applying the brakes. It will be understood that one of these improved "straight" valve mechanisms will be 105 used in connection with the automatic triple valve on each individual car.

The amount of overcharge air pressure added to the train line pressure as above described and which is necessary to set the brake with my improved "straight" air valve, also increases the air pressure in the auxiliary reservoir through the seepage groove in the piston chamber of automatic triple valve. When the train line air pressure is again reduced to normal through the 10 action of the engineer's valve being placed in running position, the excess air pressure contained in the auxiliary reservoir passing through port 5 seats valve 4 and closes port 7. A vent 11^a is provided in plug 11 for the 15 release of air left in bore 9 and passage 18. The pressure in the brake cylinder then takes effect, and forces the cylindrical piston valve 10 to normal position which then opens exhaust port 12 releasing the air from 20 the brake cylinder to the atmosphere, thus releasing the brake. It will thus be seen that it depends entirely on the amount of excess air pressure which the engineer adds to the train line air pressure how hard the 25 brakes are set on each car, as he has complete control over this by the use of the engineer's brake valve on the engine.

As before mentioned, by the use of my attachment or straight air valve the brakes 30 can be applied by both the use of straight air and automatic air. Straight air can be applied to the brakes and automatic air applied on top or automatic air can be applied to the brakes and straight air can be applied 35 on top, but by the use of my valve it is best to use straight air in all cases, thereby having the automatic air in reserve in case of accident, such as the parting of a hose or breaking of a train pipe. As is clearly seen, 40 the auxiliary reservoir is kept charged by the use of my valve. Thus it acts as a safety device in case of accident.

With the present system of automatic air brakes it often happens on long grades that 45 the automatic air pressure contained in the auxiliary reservoir is not sufficient to hold the train, whereas by the use of my valve the engineer can apply the brakes by the use of the excess pressure sufficient to hold 50 the train and at the same time have the automatic air in reserve to set the brakes in case of accident as mentioned above. By the use of my attachment it is impossible to lose the braking power since any position 55 other than running and lap positions of the engineer's brake valve will set the brakes. Also by the use of my valve using the straight air, the pressure in each brake cylinder will be the same, whether the brake 60 cylinder piston is set to travel two inches or ten inches, for the reason that the excess air pressure applied at the engine is distributed equally through my valve to the brake cylinders, one of which is located on 65 each individual car. This prevents, to a

large extent, the parting or breaking in two of the train, as is now very often the case with the present system of automatic air.

The by-pass 8 is arranged in the wall of the casing 1 for the purpose of allowing the 70 auxiliary reservoir air pressure coming through the port 5 to be equalized on both sides of the weighted piston valve 4 when it is seated on the port 7.

I claim:

1. In a valve mechanism for air brakes, a casing provided with a main valve chamber, a weighted valve disposed in said chamber, packing rings for said valve, a by-pass in the wall of the casing around said valve 80 when the latter is in its lower position, a pipe for connecting one end of said valve casing with a supply of compressed air, a passage within said valve casing normally closed by said weighted valve and adapted to be uncovered by an overcharge of air pressure in the passage, an outlet pipe, and means for establishing communication between said main valve chamber and said outlet pipe, said means being controlled by 85 the pressure of air in said main valve chamber.

2. In a valve mechanism for air brakes, a casing provided with a main valve chamber, a weighted valve disposed in said chamber, packing rings for said valve, a by-pass in the wall of the casing around said valve when the latter is in its lower position, a pipe for connecting one end of said valve casing with a supply of compressed air, a 95 passage within said valve casing normally closed by said weighted valve and adapted to be uncovered by an overcharge of air pressure in the passage, an outlet pipe, and means for establishing communication between said main valve chamber and said outlet pipe, said means being controlled by 100 the pressure of air in said main valve chamber.

3. In a valve mechanism for air brakes, a

casing provided with a main valve chamber, a weighted valve disposed in said chamber, packing rings for said valve, a by-pass in the wall of the casing around said valve when the latter is in its lower position, a pipe for connecting one end of said valve 115 casing with a supply of compressed air, a passage within said valve casing normally closed by said weighted valve and adapted to be uncovered by an overcharge of air pressure in the passage, an outlet pipe, means for establishing communication between said main valve chamber and said outlet pipe, said means comprising a piston 120 valve disposed within a bore in said valve casing, a passage connecting said main valve casing with said bore, and a passage arranged to be uncovered by the movement of said piston valve for connecting said bore with said outlet pipe.

4. In a valve mechanism for air brakes, a

- casing with said bore, a passage arranged to be uncovered by the movement of said piston valve for connecting said bore with said outlet pipe, and an exhaust passage normally uncovered and adapted to be covered when the piston valve uncovers the passage between the interior of the bore and the outlet pipe, said exhaust passage being uncovered by the reverse movement of said piston valve.
5. In a valve mechanism for air brakes, a casing provided with a main valve chamber, a weighted valve disposed in said chamber, packing rings for said valve, a by-pass in the wall of the casing around said valve when the latter is in its lower position, a pipe for connecting one end of said valve casing with a supply of compressed air, a passage within said valve casing normally closed by said weighted valve and adapted to be uncovered by an overcharge of air pressure in the passage, an outlet pipe, means for establishing communication between said main valve chamber and said outlet pipe, said means comprising a piston valve disposed within a bore in said valve casing, a passage connecting said main valve casing with said bore, a passage arranged to be uncovered by the movement of said piston valve for connecting said bore with said outlet pipe, an exhaust passage normally uncovered and adapted to be covered when the piston valve uncovers the passage between the interior of the bore and the outlet pipe, said exhaust passage being uncovered by the reverse movement of said piston valve, 35
4. In a valve mechanism for air brakes, a casing provided with a main valve chamber, a weighted valve disposed in said chamber, means for establishing communication between that part of said main valve chamber above the valve and an auxiliary reservoir, a by-pass in the wall of the casing around said valve when the latter is in its lower position, a pipe for connecting one end of said valve casing with a supply of compressed air, a passage within said valve casing normally closed by said weighted valve and adapted to be uncovered by excess air pressure in the passage, an outlet pipe, and means for establishing communication between said main valve chamber and said outlet pipe, said means being controlled by the pressure of air in said main valve chamber.
